DESIGN FOR A TARGET GAME BOARD

Emil E. Rost, Cicero, Ill.

Application May 21, 1934, Serial No. 51,862

Term of patent 3½ years

To all whom it may concern:

Be it known that I, EMIL E. ROST, a citizen of the United States, and resident of Cicero, in the county of Cook and State of Illinois, have invented a new, original, and ornamental Design for a Target Game Board, of which the following is a specification, reference being had to the accompanying drawing, forming a part thereof.

Figure 1 is a front elevational view of a game board showing my new design; and

Fig. 2 is a cross sectional view of my game board taken on line 2—2 of Fig. 1.

I claim:

The ornamental design for a target game board, substantially as shown.

Signed at Chicago, in the county of Cook, and State of Illinois, this 16th day of May, A. D. 1934.

EMIL E. ROST.
